JOSEPH RAVENNA, OF PHILADELPHIA, PENNSYLVANIA, ASSIGNOR OF ONE-HALF TO
WILLIAM A. GRAHAM, JR., OF GERMANTOWN, PENNSYLVANIA

BURNER NOZZLE

Application filed May 13, 1931. Serial No. 537,136.

The present invention relates to an improved burner nozzle for burning fuel crude oil for the purpose of generating intense heat for various purposes.

5 One of the purposes of the invention is to provide a burner nozzle including a casing, a fuel conducting tube in the casing, and a rotor in the casing rotatably mounted on the conducting tube, the rotor fitting in a restricted end of the casing in such a manner as to provide for a restricted outlet space, through which air under pressure is allowed to pass, and providing for an injector action or entraining action of the air with the fuel 10 at the outlet end of the nozzle, acting to materially volatilize and vaporize the fuel, facilitating ignition of the mixture adjacent the outlet end of the nozzle. In this manner a highly combustible gas is generated.

15 Another purpose is to provide a fuel conducting tube, about which the rotor operates revolubly, the rotor having a mixing chamber, while the fuel conducting tube is provided with discs, varying in diameter, and 20 certain of which act to regulate the oil film on the interior surface of the mixing chamber of the rotor, while others of said discs act to prevent the flame from entering the chamber.

25 It is to be understood that the particulars herein given are in no way limitative, and that while still keeping within the scope of the invention, any desired modification of details and proportions may be made in the 30 construction of the appliance according to circumstances.

The invention comprises further features and combination of parts to be hereinafter set forth, shown in the drawings and claimed.

35 In the drawings:—

Figure 1 is a perspective view of the improved burner nozzle constructed in accordance of the invention, attached to a gun.

40 Figure 2 is a longitudinal sectional view on line 2—2 of Figure 1.

Figure 3 is a cross sectional view on line 3—3 of Figure 2.

Figure 4 is a sectional view on line 4—4 of Figure 2.

45 Referring to the drawings, 1 identifies a

casing, which may be any suitable shape, preferably of the contour shown and which may be any size. The large end of the casing is provided with a plurality of openings 2, through which air under pressure passes. The casing 1 at its head 3 is provided with an annular flange 4, which constitutes a bearing for a rotor 5.

The end of the casing 1 opposite the head 3 is provided with a restricted portion 6, in which the end 7 of the rotor is positioned, in such a manner as to provide a substantially restricted space 8.

Connected to the head 3 at 9 is a fuel conducting tube 10 provided with a duct or passage 11. This tube passes through the center of the rotor, there being a collar 12 on the tube, for cooperation with the shoulder 13 of the rotor to retain the rotor in position and to hold the same in its bearing adjacent the head 3 of the casing. The fuel conducting tube passes through a chamber 14, into which the fuel oil passes. The fuel oil passes out the jet openings 15 formed in the peripheral edge of a hollow disc or flange 16 carried by the fuel conducting tube. Where the fuel conducting tube passes through the chamber 14, it is provided with a head or an enlargement 17 comprising a plurality of discs or collars 18, with intermediate discs 19. In the operation oil under pressure enters the duct or passage 11 of the tube 10, and it escapes through the jet openings 15 with substantial force, and while the chamber 14 may comparatively fill up with oil, the oil jets from the openings 15 will impinge the interior cylindrical surface of the wall of the chamber 14 with sufficient force, tending to break up the oil. However while the oil may be broken up in this manner a film of oil collects on the interior cylindrical surface of the wall of the chamber 14 due to the centrifugal action. It will be noted that the first two discs or collars nearest the hollow flange 16 are of different diameters. The first one adjacent the hollow flange 16 is smaller in diameter than the next collar or disc 18. Being that the first collar is of smaller diameter than the next, therefore its cylindrical surface being spaced a greater

distance from the interior cylindrical surface of the wall of the chamber 14, a heavier film of oil will collect on the interior cylindrical surface of the wall of the chamber. 5 This film of oil gradually feeds out toward the outlet of the chamber 14, and as the film travels in said direction the next collar or disc being of a larger diameter, therefore the space between its cylindrical surface and the 10 wall of the chamber being substantially narrower, the film of oil on the interior surface of the wall of the chamber 14 will be substantially thinned out. The disc or collar 18 next to the outermost disc or collar at 15 the outlet end of the chamber 14 is of the same diameter as the first collar or disc, therefore the space between its cylindrical surface and the wall of the chamber 14 is the same as the space between the first collar 20 or disc 18 and the wall of the chamber, therefore allowing easy passage of the thinner film of oil. However should the film increase at this point, the outermost disc or collar 18 at the outlet end of the chamber 14 will again 25 act to cut down or thin out the film of oil. In addition to this function of the outermost disc or collar, it also prevents the flame from entering the chamber. The film of oil leaves the outlet end of the chamber and is thrown 30 off as a result of the centrifugal action, while the air from the restricted space 8 discharges in a similar manner, and mixes with and volatilizes the oil as it leaves the outlet end of the chamber 14, and in this manner producing 35 a combustible burning mixture, the ignition of which generates intense heat for various purposes.

The rotor is provided with a plurality of radial blades 21, with which the air entering 40 through the openings 2 at the head 3 impinge, hence imparting movement to the rotor, the rapid rotation of the rotor acting to agitate the fuel oil in the chamber 14. The head 3 has an extension 22, which may support 45 the burner nozzle as shown.

The extension 22 of the head 3 passes through the closed end of an air conductor 24. The closed end 26 of the air conductor is provided with openings 27 to register with 50 the openings 2, and in this way air under pressure passes into the chamber of the casing 1 wherein the blades 21 of the rotor operate, to impart movement to the rotor.

An elbow 25 is threaded to the extension 55 22 to support the burner nozzle casing 1. A pipe 23 from any suitable oil supply passes through the wall of the air conductor 24 and is threaded to the elbow. The elbow 25 acts to clamp the head 3 of the burner nozzle casing closely in contact with the closed end 60 26.

The invention having been set forth, what is claimed is:

1. A burner nozzle, comprising a casing 65 provided with an air chamber with air inlets

at one end, permitting air under pressure to enter the chamber, an oil tube for conducting oil under pressure arranged axially with the air chamber, a rotor revoluble on the oil tube with blades with which the air passing through the air chamber impinges for imparting movement to the rotor, said air chamber having a restricted outlet at one end, the rotor extending into and fitting relatively close within said restricted outlet, the extended part of the rotor having a fuel chamber, said oil tube having a hollow flange provided with radial oil jet openings located at the inner end of the fuel chamber, whereby jets of oil are directed toward the inner surface of the fuel chamber, said oil tube having an extension with means thereon for determining the depth of the oil film collecting on the inner cylindrical surface of the wall of the fuel chamber. 70 75 80 85 90 95 100 105 110 115 120 125 130

2. A burner nozzle, comprising a casing provided with an air chamber with air inlets at one end, permitting air under pressure to enter the chamber, an oil tube for conducting oil under pressure arranged axially with the air chamber, a rotor revoluble on the oil tube with blades with which the air passing through the air chamber impinges for imparting movement to the rotor, said air chamber having a restricted outlet at one end, the rotor extending into and fitting relatively close within said restricted outlet, the extended part of the rotor having a fuel chamber, said oil tube having a hollow flange provided with radial oil jet openings located at the inner end of the fuel chamber, whereby jets of oil are directed toward the inner surface of the fuel chamber, said oil tube having an extension with means thereon for determining the depth of the oil film collecting on the inner cylindrical surface of the wall of the fuel chamber, and to prevent the flames from entering the fuel chamber. 110 115 120 125 130

3. In a burner nozzle, the combination with a casing provided with an air chamber with a restricted air outlet at one end and air inlets at the other end, whereby air under pressure may enter the chamber, of an oil tube supported axially with the air chamber for conducting oil under pressure, a rotor supported on the oil tube and having one end extending into and fitting relatively close in the restricted air outlet, said rotor having radial blades, with which the air passing through the chamber impinges for imparting revolvable movement to the rotor, one end of the rotor having a fuel chamber, said oil tube having means located in the fuel chamber for directing jets of oil on the interior cylindrical surface of the fuel chamber, whereby through the medium of centrifugal action a film of oil may spread on the interior cylindrical surface of the fuel chamber and feed toward the outlet end of the fuel chamber, said oil tube having an extension in the oil 130

chamber, and means on said extension and within the fuel chamber for determining the depth of the oil film as it feeds to the outlet end of the fuel chamber.

- 5 4. In a burner nozzle, the combination with a casing provided with an air chamber with a restricted air outlet at one end and air inlets at the other end, whereby air under pressure may enter the chamber, of an oil tube
10 supported axially with the air chamber for conducting oil under pressure, a rotor supported on the oil tube and having one end extending into and fitting relatively close in the restricted air outlet, said rotor having
15 radial blades, with which the air passing through the chamber impinges for imparting revoluble movement to the rotor, one end of the rotor having a fuel chamber, said oil tube having means located in the fuel chamber, for
20 directing jets of oil on the interior cylindrical surface of the fuel chamber, whereby through the medium of centrifugal action a film of oil may spread on the interior cylindrical surface of the fuel chamber and feed
25 toward the outlet end of the fuel chamber, said oil tube having an extension in the oil chamber, and means on said extension and within the fuel chamber for having a part thereof for determining the depth of the oil
30 film only as it feeds toward the outlet end of the fuel chamber, and means on said extension beyond the first for preventing the flames from entering the fuel chamber.

In testimony whereof he affixes his signature.

JOSEPH RAVENNA.
